UNITED STATES PATENT OFFICE.

WALTER HUELLER, OF WEEHAWKEN, AND MAX KRAPP, OF UNION HILL, NEW JERSEY.

EMBROIDERY-MACHINE.

1,300,838.

Specification of Letters Patent. Patented Apr. 15, 1919.

Application filed March 22, 1915. Serial No. 16,263.

To all whom it may concern:

Be it known that we, WALTER HUELLER, a citizen of the German Empire, and residing at Weehawken, in the county of Hudson 5 and State of New Jersey, and MAX KRAPP, a citizen of the United States, and residing at Union Hill, in the county of Hudson and State of New Jersey, have invented certain new and useful Improvements in Embroidery-Machines, of which the following is a 10 specification.

This invention relates to improvements in and relating to embroidery machines, and has for its object to provide automatic enlarging means and means whereby the pantograph action used in connection with the embroidery machines and the apparatus for making jacquard cards to be used in such machines may be so carried out as to have a 15 minimum of friction, and thereby enable more accurate and quicker work than has heretofore been possible. In the use of pantographs such as those heretofore used on embroidery machines, considerable energy is necessary on the part of the operator, 20 to manipulate the handle of the pantograph, and the pantograph itself, so that the muscles of the operator became fatigued, and in consequence, it has been found that not only 25 does the pantograph lack sensitiveness, but that those skilled in the action of pantographs and the art of manipulating the same have only a limited life of usefulness in view of the exacting nature of the services. 30 The object of the present invention, therefore, is to render the action of the pantograph so delicate that it may be readily moved without the slightest fatigue, and at the same time, be very accurate. A further 35 object is to provide such a device which may be adaptable in its use to a number of purposes; for instance, to operate a single machine of the present type; to operate a number of machines simultaneously by the use 40 of a single pantograph; to operate a jacquard card punching machine; to make enlarged drawings from original designs; and other similar uses may be resorted to, which 45 will become obvious from the following disclosure.

With these and other objects in view, our invention comprises the novel features, arrangements and combinations of parts, hereinafter more fully described with reference

to the accompanying drawings, and particularly pointed out in the claims.

In the drawings,

Figure 1 is a view in elevation of the pantograph and electric connections operated by the pantograph, and which is electrically connected with mechanism for carrying out the correction;

Fig. 2 is a similar view showing a modified form of construction, in which a sample frame is in coöperation with the pantograph; and

Fig. 3 shows a form of symmetrical design made by one embodiment of our invention.

Similar reference characters indicate corresponding parts throughout the several figures of the drawings.

Referring to the drawings, and more particularly to Fig. 1, the sample or design 10, which is applied to the stationary frame 11, 75 serves as a guide for the operation of the machine, as is well known. In a plane parallel with the plane of the frame 11, which supports the design or sample 10, the pantograph frame 12 is provided, which 80 is delicately supported so that the slightest movement thereof, either vertically up or down, or horizontally to the left or right will be transmitted.

The pantograph frame 12 is provided at 85 its lower end with a magnifying glass 13, through which a pointer 14 is visible, which pointer 14 follows the design or the threads of the sample. A handle 15 serves to enable the frame to be moved. Above the magnifying glass 13 and handle 15, a horizontal slotted bar 16 is provided, in which rollers 17 and 18 are freely movable, which 90 rollers 17 and 18 are secured to members 19 and 20, which in turn are part of segments 21 and 22, which are pivoted at 23 and 24. To each of the segments 21 and 22 a guide rope or cable 25 and 26 is secured, which 95 guide ropes or cables pass over spring-actuated drums 27 and 28 at the upper part of the frame, and pass over guide pulleys 29 and 30. It will be noted that the movement of the guide rollers 17 and 18 may freely take place in the slotted bar 16 100 when the slotted bar 16 is moved horizontally from the left to the right, or from the right to the left, but if the slotted bar 16 is moved vertically upwardly or downwardly,

it will carry the rollers 17 and 18 and move the segments 21 and 22 around their pivots 23 and 24, and hence move the guide ropes or cables 25 and 26 correspondingly. As 5 the segment 22 is moved, the pointer 31, secured to the shaft 24, moves with it, and this pointer moves over an arc-shaped bar 32. The bar 33 is formed of insulating material, and contact members 40 are provided in spaced relation thereon, and are adapted to be individually and successively engaged by the pointer 31 during its movement. Wires 41 connect the contact members 40 respectively with a plurality of electromagnets 34, which are grounded upon a plate 44^a arranged concentrically about a wheel 35^a mounted upon a shaft 35, upon which there is provided a bevel gear 36 which engages a bevel gear 37, mounted 10 upon a shaft 37^a which is operatively connected to the frame of the embroidery machine or other mechanism (not shown) to be operated correspondingly to the movement of the frame 45.

15 The bar 32, which is of conducting material, is connected by a wire 43, in which there is arranged a source of electricity 43^a to the plate 44^a upon which the electromagnets 34 are grounded by means of a connection 44, provided on an arcuate plate 44^a. Thus the electromagnets are individually and successively energized as the pointer 31 moves from one contact point 40 to the next. The armatures 35^b are provided on the periphery of the wheel 35^a, which are attracted by the energized electromagnets 34, moving from one to the next as they are successively energized, thereby turning the wheel 35^a.

20 25 When, however, the handle 15 is pressed so as to guide the frame 12 either from the left to the right or from the right to the left, the slotted portion 16 of the frame 12 is freely movable with respect to the guide rollers 17 and 18, so that the segments 21 and 22 are not operated. On the other hand, however, the slotted bar 45, extending vertically upwardly from the slotted bar 16 and at right angles thereto, has a guide 25 wheel 46 movable therein, and which guide wheel 46 is secured to a bar 47 movable between guide rollers 48 and 49, and having a rack 50. Guide rollers 51 are arranged at each side of the vertical bar 45. Thus, 30 the movement of the slotted bar 45 in the vertical direction permits the relative movement of this bar to the guide roller 46, without in any manner influencing the position of the bar 47, but any movement of the slotted bar 45 from the left to the right or from the right to the left, carries with it the guide roller 46 and the bar 47 in a manner 35 so as to move the rack 50 from the right to the left or from the left to the right. A pinion 53 engages the rack 50, and to this pinion

is secured a pointer 54, which passes over an arc-shaped contact member 55, similar to that indicated by 32. The bar 56 is formed of insulating material, and contact members 59 are provided in spaced relation thereon, and are adapted to be individually and successively engaged by the pointer 54. Wires 60 connect the contact members 59 respectively with a plurality of electro-magnets 61 which are grounded upon a plate 61^a, arranged concentrically about a wheel 62^a mounted upon a shaft 62, upon which there is provided a bevel gear 63 which engages a bevel gear 64 mounted upon a shaft 64^a, which is operatively connected to the frame of the embroidery machine or other mechanism (not shown), to be operated correspondingly to the movement of the frame 45.

The bar 55, which is of conducting material, is connected by a wire 57, in which there is arranged a source of electricity 60^a to the plate 58^a upon which the electro-magnets 61, are grounded by means of a connection 58 provided on the arcuate plate 58^a. Thus the electro-magnets are individually and successively energized as the pointer 54 moves from one contact point 59 to the next. The armatures 62^b are provided on the periphery of the wheel 62^a, which are attracted by the energized electromagnets 61, moving from one to the next as they are successively energized, thereby turning the wheel 62^a. Thus, by giving the slotted bar 45 a movement from the left to the right, the corresponding movement of the frame of the embroidery machine results. Or by giving the slotted bar 45 a movement from the right to the left, a corresponding movement of the embroidery frame of the embroidery machine results.

It will thus be noticed that a very slight movement in either vertical or horizontal direction would be transmitted by the electro-magnetic means to the frame of the embroidery machine, and it will be noticed that a very slight movement only is necessary to operate the pantograph frame 12, and its movement will control the electrical energy, so that the electrical energy will cause the movement of the frame of the embroidery machine instead of the physical energy necessary, as resulting from the hand of the operator, as heretofore.

One of the advantages of this construction is that the slightest movement will be quickly transmitted and very little energy is necessary to bring about this movement, and the operator will feel less fatigued than otherwise.

The ratio between the design or sample on the board and the pointer moving over the electro-magnets, and the action transmitted by the gears and the embroidery being worked on the machine, must be such that 130

the completed embroidery must be the size of the original design, whether or not the sample on the board is exact size or enlarged size. It will be seen that this ratio may be 5 changed as desired to make enlarged drawings from a given design, for instance, by moving a frame under a pencil, or to operate an embroidery machine or jacquard card punching machine, either from the original 10 design or an enlarged design, and by means of the electrical connections, several of these different operations may be carried out simultaneously. These advantageous features will be readily appreciated when it is 15 considered that enlarged designs for use on the machines at present in use must be made at an expense of hundreds of dollars in many cases.

In Fig. 2 an embodiment of the same idea 20 is shown, in which a sample of the embroidery is worked upon a piece of material, while the original design is being followed by the operator. At the present time, a new design is first worked on a piece of material by embroidery machines, and this is used for obtaining orders, after which enlarged drawings, indicating each stitch, must be made for use on the large embroidery machines. With our invention, the 25 sample may be made from the original design, and at the same time, an enlarged drawing is made indicating each stitch, so that after orders are obtained from the sample, the embroidery made from the drawing 30 will be exactly as represented. This is very often not the case at present, because one operator makes the sample, and another the drawing, and as a result, the number and direction of the stitches are changed. 35 This form may be used in connection with jacquard card punching machines, so that when the design is completed, any mistakes or omissions may be noted on the sample, and the card corrected before being used in 40 the embroidery machine.

In this embodiment, a frame 80 is provided, which has slotted portion 81 engaging a guide roller 82 on a bar 83, pivoted at 84, which bar 83 is bent angularly into 45 the shape as indicated by 85. The end of the bar 85 is pivotally connected at 86 to a link 87, the lower end of which is pivotally connected with the sliding contact block member 88. This contact member slidably 50 engages a slot 89^a in a bar 89, and has a pointer 90 which passes over a plurality of contact pieces 91, all supported on the bar 92. When the frame 80 is moved from the left to the right or from the right to the 55 left, the bar 83, 85, and link 87 are moved, and the pointer 90 is moved along the contact pieces 91, and closes electrical contact in the manner described in connection with Fig. 1. The frame 80 is provided at its upper 60 end with a slotted portion 93, which is

engaged by a roller 94 on a bar 95 pivoted to the pin 96, which bar 95 extends into a portion 97 pivotally connected at 98 to a link 99 which is pivotally connected at 100 to a sliding block 101 slidably engaging a slot 104^a in a frame 104 and having a pointer 102 passing over a plurality of contact pieces 103 on the frame 104. These contact pieces 103 are connected with suitable electrical connections which operate 75 with electro-magnets in the manner described in connection with Fig. 1.

Thus, any horizontal movement from the left to the right is translated by means of the bar 83, 85 and link 87 to the pointer 90, 80 and vertical up or down movement is translated by the bars 95, 97, and 99 to the pointer 102. The frame is further provided with a magnifying glass 105, handle 106, a pointer 107, in a manner similar to that shown in 85 Fig. 1, and acting in a like manner in respect to the design or sample 108. The frame 80 has its slotted bar 93, as also an additional slotted bar 193, engaged by guide rollers 110, 111, 112 and 113, which are supported by arms 114, 115, 116, 117, pivoted at 118, at 119, at 120, and at 121, and which are provided with guide wheels 123, 124, 125, 126, over which a rope or cable, or cord 127 passes. To the ends of this rope or cord 127 90 weights 128 and 129 are secured, and these weights, together with the rope or cable or cord 127, serve to hold or balance the frame 80 in position, the rollers 110, 111, 112 and 113 acting as an additional guide means so 95 as to facilitate the movement of the frame as it is moved by the handle 106, and as it performs its function of translating its mechanical movement to the pointer 88 and 101, the mechanical movement of which controls the electrical movement in the operations heretofore described in connection with Fig. 1.

The frame 80 is also provided with a cross-bar 130, which helps to support a piece of 110 fabric 131, behind which is arranged a series of embroidery needles (not shown) sufficient to work on the fabric during the movement of the frame a sample of the design.

By the device just described any inaccuracies found in the work produced by the embroidery machine may be readily corrected.

An enlarged drawing of a symmetrical design such as that shown in Fig. 3 may be 115 carried out from an original design of only one-half of the complete pattern, such as shown in full lines, by means of two enlarging pantograph apparatus, used instead of the usual embroidery frame connected so as 120 to be moved oppositely to each other by operation of the shafts 37^a and 64^a. The drawing apparatus operated by our device preferably consists of a pair of frames each provided with a drawing point, and movable 125

130 per end with a slotted portion 93, which is

horizontally and vertically by arms or gearing which are respectively operated proportionately to the movement of the frames of the present invention by movement of the 5 shafts 37^a and 64^a as above pointed out.

The advantages have already been pointed out and are clear, in that a very facile operation results, with a minimum expenditure of energy by the operator, and at the same time 10 increasing the efficiency and added possibilities of the machine and its accurateness.

We have illustrated and described preferred and satisfactory forms of our invention, but it is obvious that changes may be 15 made therein within the spirit and scope thereof, as defined in the appended claims.

Having thus described our invention, we claim as new and desire to secure by Letters Patent:—

20 1. In a device of the character described, the combination of a pantograph frame, means operated by the pantograph frame, electrical means controlled by said last-named means, and means operated by said 25 electrical means adapted to have a relative movement with said pantograph frame.

2. In an embroidery machine, the combination of a pantograph frame, means operated by the pantograph frame, electrical 30 means controlled by said last-named means, and means adapted to be connected with the frame of the embroidery machine operated by said electrical means.

3. In an embroidery machine, a frame 35 having guide slots arranged horizontally and vertically, means engaging said vertical and horizontal slots, electro-magnetic means set in operation by said engaging means, means operated by the electro-magnetic 40 means, and means adapted to connect said last-named means with the embroidery frame of the embroidery machine.

4. In an embroidery machine, the combination of a pantograph frame, a sample embroidery frame carried by said pantograph frame, means operated by the pantograph frame, electrical means controlled by said last-named means, and means adapted to be connected with the frame of the embroidery machine operated by said electrical means. 45 50

5. In an embroidery machine, a frame having guide slots, arranged horizontally and vertically, means engaging said vertical and horizontal slots, electro-magnetic means set in operation by said engaging means, and means operated by said electro-magnetic means adapted to have a relative movement with said frame. 55

6. In an embroidery machine, the combination of a pantograph frame, a sample embroidery frame carried by said pantograph frame, means operated by the pantograph frame, electrical means controlled by said last-named means, and means operated by said electrical means adapted to have 60 65 a relative movement with said pantograph frame.

7. In a device of the character described, the combination of a frame adapted to be moved to follow the lines of a predetermined design to be reproduced, means controlled by the movement of said frame, electrical means controlled by said last-named means, and means operated by said electrical means adapted to have a relative movement with 70 75 said frame.

In testimony, that we claim the foregoing as our invention, we have signed our names in presence of two subscribing witnesses.

WALTER HUELLER.
MAX KRAPP.
